APPARATUS FOR ENGRAVING RETICULES

Joseph O. Bluhm, Philadelphia, Pa.

Application June 25, 1941, Serial No. 399,747

6 Claims. (Cl. 33—23)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to engraving machines in general, and in particular to a means for mounting and lowering the stylus and bearings therefor.

In the usual types of engraving machines, the stylus is carried on a unit providing for motion of the stylus in a vertical plane on a pivoted arm to engage and disengage the work. The pivot bearings of such units are subject to wear thus effecting the final result at the stylus point and requiring adjustment to compensate for the wear.

This defect is remedied in the machine of the invention which provides a resilient mounting for the stylus affording a constant pressure on the pivot bearings and continuously and automatically compensating for wear in the bearings.

It is therefore an object of this invention to provide bearing mountings for the pivoted portions of engraving machines with self-adjusting features.

It is a further object of this invention to provide resilient bearing mountings for the pivoted parts of engraving machines.

It is a further object of this invention to provide a novel stylus lifting and lowering unit.

To these and other ends, the invention consists in the construction, arrangement and combination of elements described hereinafter and pointed out in the claims forming a part of this specification.

A practical embodiment of the invention is illustrated in the accompanying drawings wherein:

Figure 1 is a view in side elevation showing the stylus suspension unit and its lever system in solid lines and other portions of the engraving machine in broken lines.

Figure 2 is a broken enlarged view in side elevation of the stylus support.

Figure 3 is a top plan view of Figure 2 showing one portion of a gang stylus unit.

Figure 4 is a plan view of a portion of the transmitting structure of an engraving machine.

Figure 5 is a section taken on the line 5—5 of Figure 4, and

Figure 6 is a section taken on the line 6—6 of Figure 4.

Referring to the drawing by characters of reference, there is shown in Figure 1 the stylus unit mounted on the engraving machine, which is shown schematically. Table 1, which holds the

work 2 is reciprocated by means of a crank 3 and wormed shaft 4.

The stylus unit, or series thereof, is attached to a member 5 which is pivotably connected to the rest of the machine as at 6 in a well-known manner and controlled from a master stylus through a complex system of levers. These portions of the machine need no description, since they form no part of the invention, nor are they necessary to the understanding thereof. They have, therefore, either been omitted from the drawing or indicated generally by broken lines.

An enlarged view of the stylus unit is shown in Figures 2 and 3. The stylus 7 is held at the end of a lever arm 8 pivoted as at 9 and the stylus is urged downward by gravity aided by a supplementary weight 10. Stylus lever 8 is controlled by another lever 11 pivoted as at 12 and urged downward by gravity aided by a weight 13.

20 Lever 11 has attached to its inner end a bar 14 for contacting the lever 8 or a series thereof. This contact is actually made by means of a position adjusting screw 15. When lever 11 is raised, the adjusting screw 15 on the inner end thereof contacts the inner end of stylus lever 8 and the stylus is raised, and when lever 11 is permitted to drop, the stylus lever will likewise drop to engraving position.

Control lever 11 is manipulated by means of 30 a plunger rod 16 carrying a table-like head 17, preferably of disk form. The plunger is urged upward by means of a surrounding spring 18 (Figure 1) acting on a collar 19 fixed to the plunger rod 16. The spring 18 is housed in a 35 cylindrical chamber 20 through which the plunger rod 16 passes. Plunger rod 16 is urged downward against the spring by pressure of the operator on a member 21 pivoted to the rod 16 at its lower extremity, and the stylus is thus 40 brought to engraving position under its constant weight.

Stylus lever 8 is pivoted at 9 by means of conically pointed screws 22 threadedly carried, respectively, by a fixed upright 23 and a parallel 45 upright comprising a rear fixed portion 24 and a front portion 25 pivoted about a pin 26 which is seated in a top plate 27 straddling the uprights 23 and 24 and screw-fastened thereto. Fastened to the side of upright 24 by a screw 28 50 is a flat spring 29 which engages the side of the pivoted upright 25 and thus holds the pivot points in contact at 9 under a constant pressure irrespective of wear. Furthermore, if the stylus should encounter a flaw in the material being engraved, the spring mounting will permit it

to yield and save it from injury. Obviously, the spring shown may be replaced by other types of resilient retainers, the leaf spring being but a preferred form.

Inserted in the under side of control lever 11 is a pin or screw with a rounded head 29 for engagement with the head 17 of plunger rod 16. The disk 17 offers a considerable area of contact for the head 29 to permit contact during extensive travel of the stylus unit in all directions of its plane of motion.

In Figure 4 is shown a portion of the transmission linkage. Figure 5 is a section of a detail of the linkage of Figure 4. Arms 30, 31 are received within the openings 32, 33 of a doubly-forked seat 34 which is adjustably secured to an arm 35 of the transmission system by means of screws 36 and/or pins 37. Arms 30, 31 and the central partition 38 of seat 34 have fixed bushings 39 with flared openings 40 to receive ball bearings 41. Threaded bushings 42 and 43 are provided in the outer arms of the doubly-forked member 34. One of these bushings, 42, has a central bore 44 containing a plunger 45 urged outwardly by a spring 46. The tension on spring 46 may be regulated by screwing in either or both of the bushings 42, 43. Lock nuts 47 are provided for the threaded bushings 42, 43. By these means the friction in the pivot bearings may be adjusted and wear will be automatically compensated for.

Figure 6, a detail of another point of linkage from Figure 4 will be self-explanatory in view of the description of Figure 5, the only essential difference being that a single arm 48 is pivoted within a singly-forked member 49.

I claim:

1. In an engraving machine, a carriage and holding means for a stylus lever thereon comprising aligned and opposed pivot points to receive the stylus lever therebetween, at least one of said pivot points being resiliently mounted.

2. In an engraving machine, a carriage and holding means for a stylus lever thereon comprising aligned and opposed pivot points to re-

ceive a stylus lever therebetween, a pivoted arm mounting one of the pivot points for swinging motion toward the other point and resilient means for holding the pivoted arm and pivot point in stylus-lever-holding position.

3. In combination, a stylus lever for an engraving machine, and a pivotal mounting therefor, said mounting comprising a carriage and aligned and opposed bearing members engaging the stylus lever, holding means for each of said bearing members fixed to the carriage, at least one of said holding means comprising a swingable arm pivoted to the carriage and swingable to and from the other of said holding means, and resilient means to urge said swingable arm toward the other of said holding means and thus hold said arm and its bearing member in stylus-lever-retaining position.

4. In an engraving machine comprising a stylus lifting and lowering unit freely movable as a whole in a horizontal plane, a plunger rod with a flat table atop and transverse to the rod and a control lever pivoted on said unit, swingable in a vertical plane and with a weighted end resting on said table, said table being of sufficient extent to support the control lever in all possible positions of the same in the plane of the table, and resilient means to hold said plunger rod in a raised position against the weight of the lever arm.

5. In an engraving machine, a mounting for a stylus comprising a carriage, and opposed standards on said carriage for receiving a stylus therebetween for pivotal rotation about an axis between said standards, one of said standards being pivoted to said carriage at a point offset from said axis for swinging motion to and from the other of said standards, and resilient means on said carriage positioned to urge the pivoted standard toward the other of said standards.

6. In a mounting as in claim 5, opposed bearing means adjustably received in said standards respectively defining the line of said axis.

JOSEPH O. BLUHM.
